RAILWAY CAR

William E. Wine, Toledo, Ohio, and Cyrus
Hankins, Washington, D. C.

Application July 8, 1937, Serial No. 152,650

8 Claims. (Cl. 105—290)

Our invention relates to railway cars and more particularly to hopper cars used in the transportation of finely divided lading in bulk, such, for example, as cement.

5 One of the principal objects of the invention is to provide hopper cars with improved means at the outlet ends of the hoppers for controlling and directing the discharge of finely divided lading from the car.

10 A primary feature of the invention consists in providing a railway car having a hopper provided with downwardly converging floor sheets with means rigid with the lower end of the hopper having a portion disposed therein defining 15 two lading discharge openings and also having portions defining an open-ended chute through which lading from both of the openings is adapted to pass for discharge from the car, a pair of hinged doors being provided 20 for respectively controlling the passage of lading through the openings.

Another feature of the invention consists in providing the lower end of a hopper of a railway car with a unitary casting defining two 25 lading discharge openings respectively disposed in downwardly diverging planes, doors being hingedly mounted on the casting for controlling the passage of lading through the openings and the casting being provided with a downwardly 30 projecting open-ended extension through which lading passing through the openings is adapted to discharge from the car.

A further feature of the invention consists in providing the outlet end of the hopper with 35 means defining two lading discharge openings respectively disposed in downwardly diverging planes and having an open-ended chute through which lading from both of the openings is adapted to pass for discharge from the car, 40 mechanism being disposed within the chute for actuating doors for controlling the discharge of lading through the openings and the doors when in open position being adapted to house between them portions of the door actuating mechanism.

45 Other features of the invention, residing in advantageous forms, combinations and relations of parts, will hereinafter appear and be pointed out in the claims.

50 In the drawings,

Figure 1 is a side elevational view of the discharge end of a hopper of a railway car embodying our invention.

Figure 2 is a vertical sectional view taken on 55 line 2—2 of Figure 1.

Figure 3 is a vertical sectional view taken on line 3—3 of Figure 2.

Figure 4 is a sectional view corresponding to Figure 3 showing the doors in open position.

Figure 5 is a horizontal sectional view taken 5 on line 5—5 of Figure 1.

Figures 6, 7 and 8 are perspective views illustrating parts of the mechanism for actuating the doors.

Figure 9 is a diagrammatic side elevational 10 view of the type of railway hopper car to which our invention is particularly applicable.

Referring more particularly to the drawings, 1 designates the hoppers of the railway car which are customarily arranged in pairs on opposite 15 sides of the car center sill 2. Each of the hoppers is formed by downwardly converging floor sheets 3 and inner and outer side sheets 4 and 5, respectively. The outer side sheets incline downwardly and inwardly at a substantial angle to 20 the vertical and they are preferably provided with inwardly extending flanges 6 whereby they may be conveniently secured to the floor sheets 3. The lower portions of the inner side sheets 4 incline inwardly slightly and they are secured 25 to upturned flanges 7 with which the floor sheets are provided.

While the floor sheets of each hopper terminate in spaced relation to each other in substantially the same horizontal plane, the lower 30 portions of the inner and outer side sheets between the ends of the floor sheets are notched or cut away to receive a rigid assembly for controlling and directing the discharge of lading from the hopper. Instead of forming the assembly 35 as a unitary structure, it is preferably made in upper and lower sections 8 and 9, respectively, each of which may be conveniently formed as an integral casting.

The upper section 8 which is provided with 40 preferably vertical inner and outer end walls 10 and 11, respectively, of substantially triangular shape, has two openings 12 respectively disposed in downwardly diverging planes through which lading is adapted to discharge from the hopper. 45 On each end of the section are flanges 13, arranged in the form of an inverted V, which are rigidly secured to the side sheets of the hopper, and the lower portions of these flanges at opposite ends of the section are integrally connected 50 by flanges 14 respectively secured to the floor sheets 3 of the hopper.

Integral with the outer wall 10 and intervening between the flanges 13 secured to the outer side sheet of the hopper and the adjacent edges 55

of the lading discharge openings 12 are triangularly shaped plate portions 15 which intersect at their upper ends and there form a continuation of a member 16 which extends transversely of the hopper above the openings. Member 16 may advantageously be of inverted V shape in cross section, having downwardly diverging portions 17 which, at their outer ends, merge with the upper ends of plate portions 18 integral with the end wall 11 and intervening between the latter and the adjacent side edges of the openings 12.

Depending from adjacent the lower ends of flanges 14 of section 8 are side wall portions 19 which, together with the end walls 10 and 11, form an open-ended chute through which lading from both of the openings 12 is adapted to pass for discharge from the car. Walls 19, as well as walls 10 and 11, terminate in laterally projecting flanges 20 to which corresponding flanges 21 at the top of section 9 of the assembly are rigidly secured. Section 9 forms an extension of the chute into which the lading from the openings 12 pass and it is formed with downwardly and inwardly inclined side and end walls 22 and 23, respectively, to provide a constricted opening 24 at its lower end through which lading discharges from the car. The lower end of the inner wall of section 9 and the lower end of one of the side walls thereof are preferably formed with a groove or the like 25 for receiving the flanged upper end of a flexible boot or the like (not shown) into which it may be desirable to have the lading discharge.

Hingedly mounted on section 8 beneath member 16 thereof are a pair of doors 26 for controlling the passage of lading through openings 12. The doors preferably have a common hinge axis and each is provided with a pair of hinge straps 27 having apertures for receiving hollow hinge pins 28. Each hinge pin is supported at one end in the adjacent end wall of section 8 and at the other end in a lug 29 which is formed integrally with and depends from member 16. To prevent the hinge pins from shifting longitudinally, one or more members 30 may be inserted within each pin with its ends projecting beyond the latter so as to be bent or offset, as indicated at 31, into overlapping engagement with portions of the adjacent end wall and lug 29.

Journalized in suitable bearings 32 in the end walls of the assembly is a rotatable shaft 33 for operating mechanism to actuate the doors. This mechanism includes a crank 34, one end of which is interposed between and pivotally connected to members 35 which are mounted upon and rotatable with shaft 33. The pivotal connection between crank 34 and members 35 may be similar to the hinge mountings for the doors, having a tubular pin 36 and bendable members 37 inserted therein.

The opposite end of crank 34, which is preferably of greater width than the end thereof connected to members 35, is pivotally connected to two pairs of links 38 which are respectively connected to the doors 26. The ends of the links connected to the crank are bifurcated and the bifurcated ends of corresponding links of each pair are arranged in interleaved relation and are provided with apertures for receiving a tubular pin or the like 39 by which all of the links are pivotally connected to the crank. Members 40, having ends which may be offset, are inserted within pin 39 to prevent it from shifting longitudinally.

Each pair of links is connected to its associated door by members 41 which are screw threaded into the ends of the links and are pivotally connected to brackets 42 rigid with the outer face of the door. By having a threaded connection between the links and members 41, simple and effective means is provided for varying the effective length of the links so that the mechanism may be easily adjusted to insure tight closure of the doors.

As clearly shown in Figure 3 of the drawings, when the doors are in closed position, links 38 are disposed substantially horizontally and the pivotal connection between crank 34 and members 35 is disposed beneath shaft 33. To effect a release of the doors so as to enable them to move into open position, shaft 33 is rotated to cause the ends of the links connected to the crank to move upwardly. The various parts of the door actuating mechanism are so shaped that when the doors are open, as shown in Figure 4, they will occupy a relatively small space and, in order that the mechanism will not prevent the doors from assuming substantially vertical position when open, the doors are provided with inwardly offset portions 43 for accommodating, as well as housing, the mechanism.

The side and bottom marginal edges of the door are reversely curved, as indicated at 44, for cooperating with flanges 45 bounding corresponding edges of the openings 12 to prevent the escape of finely divided lading. While only the inner portions of the reversely curved flanges 44 along the sides of the door cooperate with the flanges 45, the walls 19 of section 8 adjacent the bottom of the openings are so shaped as to cooperate with the outer portions of the reversely curved flanges at the bottom of the door. Thus, at the bottom of the door where leakage of lading is most likely to occur, the outer as well as the inner portions of the reversely curved flange function to prevent the escape of lading. At the upper edge of each door where little, if any, lading is apt to escape, is an inwardly opening recessed portion 46 for receiving a rib or the like 47 formed on the bottom face of member 16 adjacent the lading discharge opening.

While any suitable means may be employed for rotating shaft 33 in the desired direction, it is preferred to provide the shaft exteriorly of the outer end wall of the assembly with a rigid handle or extension 48. The inner or hub portion 49 of the handle may be advantageously provided with a lug 50 which is adapted to be engaged by a dog 51 for preventing accidental or unauthorized movement of shaft 33 in a direction to permit the doors to move open. Dog 51 is pivotally mounted upon a suitable support 52, the inner end of which passes through the front wall of an outwardly offset portion 53 of the outer end wall 10 of section 8. Disposed above the dog and pivotally mounted upon a suitable support 54, also extending through the front wall of offset portion 53, is a cam 55 for locking the dog in operative position. A car seal for preventing tampering with the mechanism may be conveniently employed by providing the cam with a portion 56 having an aperture which is adapted to register with an aperture 57 formed in a lug 58 projecting laterally from the upper portion of a cover plate 59 which may advantageously overlap the outer faces of the cam and dog.

From the foregoing, it will be appreciated that, in addition to other advantages, the invention

provides a simple and rugged construction in which lading passing through two door-controlled openings is caused to discharge from the car through a single outlet with which conventional means may be associated for conveying the lading to a desired location.

What we claim is:

1. A railway hopper car having a hopper provided with downwardly converging floor sheets and with side sheets extending longitudinally of the car, the lower portions of said side sheets being respectively provided with notches of substantially triangular shape, a rigid unit disposed within said notches and having flanges respectively secured to the side sheets and floor sheets, said unit forming the outlet of the hopper and including downwardly diverging portions defining two lading discharge openings, end walls rigidly connecting said downwardly diverging portions closing the notches in the side sheets, means extending below the lower edges of the floor sheets and forming with the lower portions of said end walls an open ended chute through which lading from both of said openings is adapted to pass for discharge from the car, a member having downwardly diverging portions extending transversely of the hopper above said openings and integrally connecting said end walls, and hinge lugs rigid with and depending from said member, and doors movable to open position under the influence of gravity hingedly connected to said lugs for respectively controlling the passage of lading through said openings.
2. A railway hopper car having a hopper provided with downwardly converging floor sheets and with side sheets extending longitudinally of the car, the lower portions of said side sheets being respectively provided with notches of substantially triangular shape, a unitary casting disposed within said notches and having flanges secured to the side sheets and floor sheets, said unit forming the outlet of the hopper and including downwardly diverging portions defining two lading discharge openings and end walls integrally connecting said downwardly diverging portions closing the notches in the side sheets, a pair of doors movable to open position under the influence of gravity hingedly mounted on said casting for respectively controlling the passage of lading through said opening, and means rigid with the lower end of said casting through which lading passing through said door controlled openings is adapted to discharge from the car.
3. A railway hopper car having a hopper provided with downwardly converging floor sheets and with side sheets extending longitudinally of the car, the lower portions of said side sheets being respectively provided with notches of substantially triangular shape, a rigid unit disposed within said notches and having flanges respectively secured to the side sheets and floor sheets, said unit forming the outlet of the hopper and including downwardly diverging portions defining two lading discharge openings, end walls rigidly connecting said downwardly diverging portions closing the notches in the side sheets, and means having downwardly diverging portions extending transversely of the hopper above said openings rigidly connecting said end walls, the lower portion of said unit being provided with an opening through which lading passing through each of said first named openings is adapted to discharge from the car, and doors movable to open position under the influence of gravity hingedly mounted on said unit for respectively controlling the passage of lading through said first named openings.
4. A railway hopper car having a hopper provided with downwardly converging floor sheets
- and with side sheets extending longitudinally of the car, the lower portions of said side sheets being respectively provided with notches of substantially triangular shape, a unitary casting disposed within said notches and having flanges secured to the side sheets and floor sheets, said casting forming the outlet of the hopper and including downwardly diverging portions defining two lading discharge openings, end walls integrally connecting said downwardly diverging portions closing said notches, means extending below the lower edges of said floor sheets and forming with the lower portions of said end walls an open ended chute through which lading from both of said openings is adapted to pass for discharge from the car, a member having downwardly diverging portions extending transversely of the hopper above said openings and integrally connecting said end walls, and hinge lugs rigid with and depending from said member, and doors movable to open position under the influence of gravity hingedly connected to said lugs for respectively controlling the passage of lading through said openings.
5. A railway car having a hopper provided with side sheets and downwardly converging floor sheets, a rigid unit secured to the lower portions of said sheets and forming the outlet of the hopper, said unit having two lading discharge openings respectively disposed in downwardly diverging planes and being provided with a member extending transversely of the hopper above said openings and with portions forming a chute through which lading from both of said openings is adapted to pass for discharge from the car, hinge lugs rigid with and depending from said member and a pair of doors hingedly connected to said lugs for controlling the passage of lading through said openings, said doors having a common hinge axis and being movable to open position under the influence of gravity.
6. A railway hopper car having a hopper provided with downwardly converging floor sheets and with side sheets extending longitudinally of the car, the lower portions of said side sheets being respectively provided with notches of substantially triangular shape, a rigid unit disposed within said notches and having flanges secured to the side sheets and floor sheets, said unit forming the outlet of the hopper and including downwardly diverging portions defining two lading discharge openings, end walls rigidly connecting said downwardly diverging portions closing the notches in the side sheets, and means extending below the lower edges of the floor sheets forming with the lower portions of said end walls an open ended chute through which lading from both of said openings is adapted to pass for discharge from the car, doors movable to open position under the influence of gravity hingedly mounted on said unit for respectively controlling the discharge of lading through said openings, and mechanism carried solely by said unit and having portions thereof disposed within the chute for moving the doors to closed position, said doors when in open position being disposed in back to back relation and being respectively formed so as to provide a space for housing said portions of the mechanism.
7. A railway hopper car having a hopper provided with downwardly converging floor sheets and with side sheets extending longitudinally of the car, the lower portions of said side sheets being respectively provided with notches of substantially triangular shape, a unitary casting dis-

posed within said notches and having flanges secured to the side sheets and floor sheets, said unit having integrally connected end walls defining in part an open ended chute and being provided with two door controlled openings through which lading is adapted to pass into said chute for discharge from the car, doors movable to open position under the influence of gravity hingedly mounted on said casting for respectively controlling the passage of lading through said opening and mechanism mounted on said casting and having portions thereof disposed within the chute for moving the doors to closed position, said mechanism including members respectively pivotally connected to the doors, said doors when in open position being adapted to be disposed in back to back relation and being respectively provided with inwardly offset portions affording a housing for receiving said members 20 when the doors are open.

8. A railway car having a hopper provided with side sheets and downwardly converging floor sheets, a rigid unit secured to the lower por-

tions of said sheets and forming the outlet of the hopper, said unit having two lading discharge openings respectively disposed in downwardly diverging planes and being provided with a member extending transversely of the hopper above 5 said openings and also with portions forming an open-ended chute through which lading from both of said openings is adapted to pass for discharge from the car, a pair of doors movable to open position under the influence of gravity 10 hingedly mounted on a common axis on said member for respectively controlling the passage of lading through said openings, and mechanism carried by said unit and having portions disposed within the chute for moving the doors to closed 15 position, said doors when in open position being disposed in back to back relation and having their outer faces disposed adjacent each other and forming a space for housing said portions of the mechanism.
